UNITED STATES PATENT OFFICE.

FREDERICK E. KOHLER, OF CANTON, OHIO.

TRICYCLE.

SPECIFICATION forming part of Letters Patent No. 400,091, dated March 26, 1889.

Application filed July 16, 1888. Serial No. 280,015. (No model.)

To all whom it may concern:

- Be it known that I, FREDERICK E. KOHLER, a citizen of the United States, and a resident of Canton, county of Stark, State of Ohio, 5 have invented a new and useful Improvement in Tricycles, of which the following is a full, clear, and exact description, reference being had to the accompanying drawings, making part of this specification.
- 10 My invention relates to improvements in tricycles; and it consists in providing means for adjusting the frame to adapt it to the use of different-sized wheels, also to adapt the machine to the size of rider.
- 15 With these ends in view my invention consists in certain features of construction and combination of parts, as will be hereinafter described, and pointed out in the claims.
- Figure 1 is a front elevation of a tricycle, 20 illustrating my invention. Fig. 2 is a side elevation of same. Fig. 3 is an isometrical view of the upper portion of frame enlarged, and Fig. 4 is a side elevation of a fragment of upper front portion of back frame.
- 25 Similar letters represent corresponding parts in all of the figures of the accompanying drawings.
- A represents an inverted-**U** frame. The prongs B, passing down on either side of the 30 driving-wheel C, terminate in journal-boxes D, that embrace and support the journals of the driving-wheel shaft E, on the outer ends of which are secured cranks F and treadles G. The upper or closed end of the frame A may 35 be formed substantially as shown, the upper end of the prongs bent to overlap a cross-bar, as H, having centrally-located apertured boss J; or, if preferred, the frame may be made of cast malleable metal, with the parts B and J 40 integral.
- As a means of changing the size of the machine to suit the size of the rider, or for the purpose of using drive-wheels of different size, an adjustable frame, K, is provided of 45 the form substantially as shown, having cross-bars L, on the ends of which are loops M, to embrace the side bars or prongs, B. Centrally to said cross-bars there is provided an apertured boss, J', through which is passed the 50 handle-support O, by which said bars are spaced apart, and in which said bar is se-
- cured by pins a. Rearwardly from said bars L, and centrally thereto, are projected eyes b, in which is pivotally secured the front portion, U, of the back frame, R. 55
- The handle-support O and the handle S may be made separate and secured together by any of the well-known ways for securing such parts, or may be integral, as shown. A set-screw, S', penetrates the wall of the perforation in the boss J, by which the rod O may be secured in desired adjustment.
- It will be apparent that the object sought by the hereinbefore-described parts is to provide a convenient and economical means for 60 vertically adjusting the front end of the back frame in the frame A, for the purpose of increasing or decreasing the distance between the rider's seat and the foot-treadles for the purpose of adjusting the machine to the rider. 65 A further object of equally great importance is the fact of the adaptability of the frame A to the use of wheels differing diametrically, which adjustment may be successfully accomplished by simply slackening or turning back 70 the set-screw S' and moving the rod O up or down, as the case may be, and again securing the parts in desired adjustment by turning in the screw S'. To successfully carry out this idea of enlarging the frame by a vertical 75 adjustment of the front end of the back frame renders necessary some means by which the back frame may be lengthened that the parts may be kept in proper form, and to this end the back frame, R, is formed of a rear portion, T, and a front portion, U. 80
- The front central portion, U, is provided at its front end with upwardly and downwardly projected pivots d, loosely secured in the eyes b, the rear end terminating in outwardly- 85 turned fingers h, that embrace the edges of the side bars, k, of the rear section, T, the front ends of the side bars, k, terminating in clasping fingers or loops m, that reach across and embrace the opposite side, forming a sliding loop. The two parts T and U have corresponding perforations n, through which a clamping-bolt, p, is passed, and by which the parts are secured together. 90
- To change the size of the machine or to 95 lengthen or shorten the back frame, R, the bolt p is removed and the two parts T and U

pulled apart or pressed together, as required, and fixed in adjustment by the return of the bolt *p* in the proper perforation.

The rear portion of the frame *R* extends 5 downwardly and backwardly to the axle-shaft *V*, that supports the rear wheels, *W*. It is evident that numerous slight changes might be resorted to in the form and arrangement of the several parts described without materially departing from the scope and spirit of 10 my invention, the detail and operation of which have been so fully set forth during the description of the parts that it is not deemed necessary to more fully state them here.

15 What I do claim, and desire to secure by Letters Patent, is—

1. The combination, with the frame *A* of a tricycle, of the adjustable frame *K*, having cross-bars, as *L*, with loops to embrace the 20 parallel sides of said frame *A*, rearwardly-projected eyes to pivotally engage the front portion of the back frame, *R*, and handle-support *O*, and means for securing the frame *K* in desired adjustment in the frame *A*, substantially as set forth.

2. In combination, the inverted-**U** frame *A*, adjustable frame *K*, and means of securing said frame *K* in vertical adjustment, substantially as described, and for the purpose 25 substantially as set forth.

3. In a tricycle, a back frame composed, essentially, of the parts *T* and *U*, having the loops *m*, fingers *h*, perforations *n*, and bolt *p*, substantially as described, and for the purpose set forth.

4. The combination, with the frame *A* of a tricycle, of the adjustable frame *K*, having cross-bars *L*, with loops to embrace the parallel sides of frame *A*, back frame, *R*, pivotally secured to said frame, handle-support *O*, and 40 means for securing said frame and handle-support *O* in desired adjustment in the frame *A*, substantially as described, and for the purpose set forth.

5. The combination, with the frame *A* of a tricycle, of a frame, *K*, consisting of cross-bars formed with central apertures and provided with looped ends to embrace the parallel sides of the frame *A*, the said cross-bars constructed to pivotally engage the front portion of the back frame, a handle-support, *K*, an apertured boss, *J*, and a set-screw, *S'*, substantially as set forth.

In testimony whereof I have hereunto set my hand this 10th day of July, A. D. 1888.

FREDERICK E. KOHLER.
